UNITED STATES PATENT OFFICE.

WILLIAM DALTON, OF SCHENECTADY, NEW YORK.

WORKSHOP-VENTILATOR.

1,287,572.

Specification of Letters Patent. Patented Dec. 10, 1918.

Application filed December 14, 1917. Serial No. 207,124.

To all whom it may concern:

Be it known that I, WILLIAM DALTON, of Schenectady, New York, temporarily residing in Washington, in the District of Columbia, have invented a new and useful Improvement in Workshop-Ventilators, of which the following is a specification.

My invention relates more particularly to the novel construction of ventilating means for a forge shop, or a manufacturing building, wherein large volumes of smoke or injurious gases are liberated by furnaces or manufacturing processes.

The objects of my invention are to provide a simple and effective form of a shop roof having one or more smoke or waste gas outlet ports or vents, and partition walls arranged, within the shop, with respect to the smoke vents so as to effect a continual upward and outward flow of smoke through the ports from the building regardless of wind velocities or direction; another object is to prevent the flow of smoke from one interior section of the building to another and instead to cause an immediate upward and outward flow of waste gases; a further object is to prevent a downward and inward flow of cold air through the vents and into the building, thereby avoid a retardation to the upward and outward flow of waste gases.

In the accompanying drawings forming part of this specification: Figure 1, is a longitudinal elevation of a building, or workshop, adapted to exemplify an application of my invention, part of the building is shown broken away to illustrate a vertical longitudinal mid section thereof; Fig. 2, a transverse sectional elevation, on an enlarged scale, taken on a vertical intersecting plane indicated by the trace, A A, in Fig. 1; Fig. 3, an exterior elevation of a building showing a modification of my invention adapting its application to the form of building illustrated wherein a horizontal roof section is disposed at a considerable higher elevation than oppositely disposed sloping side roof sections; Fig. 4, a transverse section thereof when taken on a vertical plane indicated by the trace, B B; Fig. 5, a longitudinal mid sectional elevation thereof is taken on the plane indicated by the trace, D D; Fig. 6, a transverse sectional elevation showing the application of my invention to a building having a pair of oppositely disposed sloping roof sections; Fig. 7, a transverse sectional elevation giving an

exemplification when applied to a roof, formed of a plurality of flat and horizontally disposed roof sections.

In the practice of my invention, referring descriptively to the preferred arrangement when embodied in a work shop, or building, as exemplified by the accompanying drawings, I provide one or more elongated waste gas outlet ports, 1, 1^a, 1^b, 1^d, 1^e, 1^f, 1^g, which are preferably formed in a section of a building roof under which smoke, vapors or other waste gases will naturally accumulate because of their buoyancy. A roof, or section thereof, adapted to the application of my invention may be inclined at any desirable angle, as illustrated by the sloped roof sections, 2, 2^a, 2^b, 2^d, 2^e, 2^f; 2^g and 2^h, shown in the several figures. Frequently it is desirable for manufacturing purposes to construct a roof section nearly flat and horizontal, as indicated by 2¹, 2¹; 2^m and 2ⁿ. A horizontal roof section may be disposed adjacent to a sloping roof section. Furthermore, it may be arranged between two oppositely disposed sloping sections, as indicated by the drawings. A plurality of horizontal roof sections, as 2^m and 2ⁿ, may be supported by a truss, 3ⁿ, in usual manner, as in Fig. 7, and provided with an interposed outlet port, 1^f. Two oppositely disposed outlet ports, 1^e and 1^g, separate the two outer sloping roof sections, 2^g and 2^h, from the corresponding horizontal sections. Manifestly the roof sections may be supported by other means than the trusses, 3, 3^a, 3^b, 3^d, 3^e and 3ⁿ; which are each mounted upon corresponding vertical supporting members, 4, 4^a, 4^b, 4^d, 4^e and 4^f. These vertical members also support crane ways, 5, 5^a, 5^b, 5^d, 95 and vertical disposed partitions or curtains, 6, 6^a, 6^b, 6^d and 6^e, which are attached thereto. To prevent cold air and rain from passing downwardly into the outlet ports, flat horizontally disposed port covers, 8, 8^a, 8^b, 8^d, 8^e, 8^f and 8^g, are supported by upright struts, 9, 9^a, 9^b, 9^d, 9^e, 9^f and 9^g, at a predetermined distance above the corresponding ports and roof sections as illustrated. These ports are further sheltered from a downward flow of roof water by the corresponding flashing members, 10, 10^a, 10^b, 10^d, 10^e, 10^f, 10^g, 10^h and 10ⁱ.

Manifestly the outlet ports may be made circular or rectangular as desired for convenience in construction. Preferably they are made oblong and disposed parallel with

the building so as to give the greatest amount of ventilation at the least cost of construction. Their arrangement as illustrated has proved most efficient in practice. However, 5 their construction can be modified to meet special requirements without departing from the spirit of my invention.

As indicated by the broken darts in Fig. 2, 10 outdoor air currents can pass freely in a horizontal direction over the ports and under the port covers, in a manner to cause a fluid rarefaction directly under the port and thereby induce an upward flow of waste gases that may have accumulated under the 15 roof in the vicinity of the outlet port.

The vertically disposed curtain-like partitions 6, are shown to begin at a predetermined distance above the working floor, 12, 20 so as to give a clear working space on the floor. Their upper edges, 6^a, extend upward to the corresponding port for the purpose of guiding the gases upward to the port and to prevent cross currents of air from driving the waste gases from one section 25 of the building to another, and instead cause hot gases from the furnaces, 13, 13^a, 13^b, and other sources, to rise upward, directly to the outlet ports, 1. The inclined partitions, 14, 14^a, 14^b, 14^c, 14^d and 14^e, 30 subdivide the space under the roof sections for the purpose of aiding the vertical partitions to guide the gases upward and to reduce cross air currents through the upper sections 35 of the building. The several partitions are preferably disposed parallel to the elongated ports, each other and to the sides of the building for convenience of construction and efficiency in operation as an aid to the ventilating outlet ports and in preventing undesirable cross currents in the building. 40 Such cross currents of air and waste gases are seriously objectionable because they carry furnace smoke from one section to all parts of the building. Instead, the partitions cause it to rise directly to the outlet ports formed in the roof.

Outdoor air is admitted through the inlets, 15, 15^a, 15^b, 15^c and 15^d, formed in the side walls of the building; preferably near the working floor level for the purpose of maintaining atmospheric pressure in the building, at the working floor level and thereby induce a prompt upward flow, of waste gases, toward the outlet ports.

55 What I claim is:

1. In a factory building having a large working floor space and a roof covering the same with ventilating openings therethrough for the free escape of fumes above the roof, 60 a means for preventing the flow of fumes laterally from one part of the building into another, and for inducing an upward movement of fumes from the working floor area, embodying side walls having air entrance 65 openings near the floor level and a curtain-

like intermediate partition extending down from the roof and terminating at its lower edge above the working floor space, the spaces at the top on both sides of said curtain-like intermediate partition being in 70 free communication with the ventilating openings.

2. In a factory building having a large working floor space and a roof covering the same with a ventilating opening therethrough for the free escape of fumes above the roof, a means for preventing the flow of fumes laterally from one part of the building to the other and for inducing an upward movement of fumes from all parts of 80 the floor area embodying external side walls extending to the roof and having air entrance openings near the floor level and a curtain-like intermediate partition extending down from the roof level and terminating at its lower edge above the working floor space, the upper edge of said partition extending across the ventilating opening 85 whereby the spaces on opposite sides of the partition both communicate freely with the 90 ventilating opening.

3. A factory building having a large working floor space and embodying inclosing walls with air inlet openings, a roof forming a cover for the building and having 95 an outlet port for the free escape of fumes above the roof and a plurality of fume-guiding partitions within the building, said partitions extending substantially throughout the building above the working floor space and 100 converging toward and terminating at their upper edges in proximity to the port, whereby all the spaces defined by the partitions are open at the top to the outlet port and fumes rising in different parts of the building 105 are guided to the outlet port without opportunity for accumulation by lateral movement within the building above the working floor space.

4. A factory building having a large working floor space and embodying inclosing walls with air inlet openings, a roof forming a cover for the building and having an outlet port for the free escape of fumes above the roof, a vertically arranged fume 115 guiding partition extending from the outlet port down into the building to a point above the working floor space and an inclined fume-guiding partition in the space between the vertical partition and side of the building, the spaces on both sides of said partitions being open to the outlet port at the top and to the working floor space at the bottom, and said partitions extending substantially throughout the building above the 120 working floor space.

5. A factory building having a large working floor space and embodying inclosing walls with air inlet openings, a roof forming a cover for the building, and having an 130

elongated outlet port for the free escape of fumes above the roof, a fume-guiding partition within the building extending substantially throughout the building above the working floor space parallel with the longitudinal axis of the port and at its upper edge terminating in proximity to said port, leaving an unobstructed passage on each side between the space divided by the partition and the port for the escape of fumes,

said partition at its lower edge terminating above the working floor space of the building, whereby fumes rising above said floor space on either side of the partition will be guided to the port and lateral movement of such fumes within the building prevented.
